UNITED STATES PATENT OFFICE.

MAXIMILIAN KOTYRA, OF PARIS, FRANCE.

MEANS FOR PERFORATING SLIPS FOR TELEGRAPHIC SIGNALING AND OTHER PURPOSES.

No. 895,374.

Specification of Letters Patent.

Patented Aug. 4, 1908.

Application filed December 3, 1906. Serial No. 346,152.

To all whom it may concern:

Be it known that I, MAXIMILIAN KOTYRA, a citizen of the Republic of France, residing at 26 Avenue des Ternes, in the city of Paris, France, have invented new and useful Improvements in Means for Perforating Paper Slips for Telegraphic Signaling and other Purposes, of which the following is a specification.

In telegraphy according to conventional signs, for instance the signs of the Morse system, a known method consists in preparing a perforated slip of paper, wherein a perforation or group of perforations each conventionally represent a given sign, and in 15 then turning over the so prepared slip to a translating apparatus which automatically conveys and reproduces the signs at a distance on a slip of paper at the receiving station. Rapidity is secured by preparing simultaneously a given number of such 20 perforated slips and in turning over each of them to a separate translator, so that the same message may be sent off in different directions and received at different stations. 25 To my knowledge, these perforated slips are prepared by hand, that is to say a punching machine is provided, wherein say three punches are made to act upon the paper slip under the effect of corresponding keys. The 30 operator, seizing a suitable instrument in each hand, strikes blows upon the keys and produces holes in the paper slip corresponding to the keys struck, the slip being automatically advanced at every blow. In addition to satisfying the main condition of 35 displaying considerable muscular power in performing the work, the operator necessarily requires to be acquainted with the Morse or other alphabet and to exercise his mind and 40 memory for every letter or sign.

An attempt has already been made to actuate the punches mechanically for the purpose of obviating the said expenditure of muscular power, by means of a pneumatic 45 apparatus which, controlled by hand by means of a set of keys, strikes blows on the keys of the perforator, see Thomas' *Traité de Télégraphie Électrique*, Paris, 1894 (Baudry & Co.) page 508, Fig. 401. Although such 50 pneumatic operation of the keys of the perforator relieves the operator, yet it compels him to be familiar with the Morse or other conventional alphabet of signs employed.

The object I have in view is not only to 55 relieve the operator from expenditure of

muscular power, but also to enable him to operate the keys of the perforator without having any knowledge of the conventional alphabet, while at the same time considerably increasing the rapidity of the perforating operation.

Broadly speaking, the invention consists in a system comprising, as its main elements, a perforator, a keyboard mechanism, an electro-magnetic appliance inserted between the perforator and the said mechanism, and a source of electric energy.

In the accompanying drawings, Figure 1 is a diagram showing an installation in accordance with the present invention, all the parts being at rest. Fig. 2 is a similar diagram with some parts in their operating position. Fig. 3 is a partial side view of Fig. 2, in section on the broken line 3—3. Fig. 4 on a larger scale, shows the perforator and the electro-magnetic appliance, in side elevation with reference to Figs. 1 and 2. Fig. 5 is a top view of Fig. 4, the electro-magnetic appliance being removed. Fig. 6 is a similar view to Fig. 4, with some parts in their operating position, in section on the line 6—6 of Fig. 7. Fig. 7 is a similar view to Fig. 5, with some of the parts in their operative position, and the electro-magnetic appliance removed. Fig. 8 is a section on the line 8—8 of Fig. 7, with the paper slip partly broken away to show the punches in end elevation.

The perforator may be of any approved kind, such for instance as the Wheatstone perforator described in British Patents No. 1239 dated June 2 1858 and No. 220 dated Jan. 28 1867. As this apparatus is known, a general outline of the same, sufficient for the comprehension of the present invention, will 90 alone be given. It consists of a box 1 wherein are arranged three keys 2, 2^a, 2^b, the levers 3, 3^a, 3^b of which can be made to actuate a series of punches, in any conventional number, say four, designated 4, 4^a, 4^b, 4^c, 100 Fig. 8 by means of which the slip of paper 5 is perforated. The punches 4, 4^a and 4^b produce holes 6 grouped according to the Morse or other conventional alphabet, while the center punch 4^c produces a series of consecutive perforations 7 by means of which, on the one hand, the paper slip 5 is fed through the perforator and, on the other hand, the letters or signs are separated from each other, as shown in Fig. 8. The punches 105

are fitted to slide in two stationary plates 8, 9. The center punch 4^a is fast with a movable plate 10 which may slide along guide-pins 11, 12 fitted in the stationary plates 8, 9 (not shown in Figs. 5 and 7). After having been pushed forward in the perforating action, the center pin 4^a is returned to its initial position by means of springs 13, 14 slipped over the guide-pins 11, 12, the said plate 10 also returning the other punches owing to the latter being provided with shoulders 15 bearing against said plate. A star-wheel 16 (Figs. 5, 7 8) engages the perforations 7 of the paper slip 5 and acts to feed the slip at every depression of the keys 2, 2^a or 2^b, by means of an arm 17 pivoted at 18 and indirectly connected to a spring pawl 19 in the usual manner. The paper slip 5 coming from a reel not shown passes in front of the punches, 20 between the stationary plate 9 and an adjoining plate 20 and is guided by rollers 21, 21.

The keyboard mechanism may be substantially similar, in principle, to the keyboard transmitter described in my U. S. patent of 25 March 21 1904, No. 779223. As this mechanism is known, a general outline of the same, sufficient for the comprehension of the present invention, will alone be given. It consists of a series of keys 22, for each sign 30 of the conventional alphabet; one key alone is shown in Figs. 1 and 2 and is pivoted at 23; its underface is toothed at 24 so as to be capable of being engaged by a continually revolving broad toothed cylinder 25, and 35 said key is formed with thin portions 26, 27 coöperating with a corresponding groove 28, Fig. 3, for the purpose set forth in the said patent. A spring 29 tends to constantly press the key upward, while a spring 30 constantly 40 tends to restore the key outwards to its initial position. A yielding contact-piece 31 fastened to the key moves with the same and is capable of coming in touch with one or more stationary contacts 32, 32^a, 32^b insulated from 45 the rest of the keyboard mechanism.

In the accompanying drawing, the contacts 32, 32^a, 32^b are shown to be three in number, but this number will vary according to circumstances. The contact 32 is 50 connected by a wire 33 to an electro-magnet 34; the contact 32^a is connected by a wire 33^a to an electro-magnet 35 and the contact 32^b is connected by a wire 33^b to an electro-magnet 36, the three magnets 34, 35, 36 constituting, together with their respective armatures, 37 and 38, Figs. 4 and 6, the electro-magnetic appliance above referred to. The armatures 37 and 38 are pivoted at 39 and held in their unattracted position by a 55 spring 40. To each armature 37, 38, is connected a plunger 41, 42, 43 which passes alongside the core of one of the electro-magnets and is placed above and in a line with the keys 2, 2^a, 2^b. From each magnet leads 60 a wire 44, 45, 46 to the battery 47, the circuit

being completed by a wire 48 which connects the battery with the body of the keyboard mechanism. As is usual, condensers (not shown) are employed for obviating injurious sparking between the contacts 32, 32^a, 32^b and the yielding contact piece 31. 70

The operation is as follows: The keyboard mechanism being in its position of rest shown in Fig. 1, the operator depresses a key 22, whereby the teeth 24 of its lever are brought 75 into engagement with the teeth of the continually revolving cylinder 25 and the key is gradually moved from right to left (Fig. 2) in such a manner that the contact piece 31 is successively moved past the stationary contacts 32, 32^a and 32^b. The electro-magnets 34, 35 and 36 are thus successively energized and a blow is struck by each plunger 41, 42, 43 on the respective keys 2, 2^a, 2^b of the perforator. 80

It is obvious that the number of contacts with which the key depressed will be made to coöperate will correspond to the sign or letter to be perforated in the paper slip. That is to say, there are twenty-six sliding keys and twenty-six combinations of contacts for the letters of the alphabet and still other keys and combinations for the digits and arbitrary characters; and these various sliding keys and combinations of contacts 95 are so connected to the three magnets 34, 35 and 36, as to cause their plungers 41, 42 and 43 to operate the three pivoted keys 2, 2^a and 2^b, in such a manner as to perforate the traveling strip 5, with the proper combination of holes to represent the particular sliding key selected in the first place. In other words, a person knowing nothing about the Morse alphabet may operate my key board, and by means of only three magnets and a 100 Wheatstone perforator, may perforate a strip of paper with combinations of holes representing the various characters of the Morse 105 alphabet or any other alphabet.

The herein described invention is more especially intended for use in telegraphy, but is not necessarily limited to that art, because it is capable of being applied in all cases where it is desired to mechanically produce 110 perforations in slips or sheets of paper, cardboard or other material as used, for instance, in musical instruments, linotyping and type-casting. 115

I claim:

1. In a device of the character described, 120 the combination of three punches, three electro-magnetic devices, one for operating each of said punches, means for simultaneously restoring said punches to their normal position, means for supporting and feeding the strip to be punched, a plurality of movable and depressible keys adapted to be connected to each of said magnetic devices, and means whereby each key when depressed 125 will bring into operation the appropriate 130

combination of electro-magnetic devices to operate the proper combination of punches corresponding to the particular key depressed, substantially as described.

5 2. In a device of the character described, the combination of paper supporting and feeding means, three punches arranged in series; one electro-magnetic device for operating each of said punches; spring-controlled means for restoring said punches to their normal position; a series of movable and depressible keys connected to each of said magnetic devices, and each provided with a contact strip; means whereby upon 10 15 the depression of a particular key said key

will be moved to bring into operation the appropriate combination of electro-magnetic devices corresponding to said key; and springs for restoring said keys, electro-magnetic devices, paper feeding means, and punches to their normal positions, substantially as described. 20

In witness whereof I have hereunto set my hand this 21st day of November 1906 in presence of two subscribing witnesses.

MAXIMILIAN KOTYRA.
